F. A. BROWN

WIRE GROUNDING DEVICE

Filed April 23, 1923

Inventor
Fred A. Brown
by his Attorney

UNITED STATES PATENT OFFICE.

FRED A. BROWN, OF LOS ANGELES, CALIFORNIA.

WIRES-GROUNDING DEVICE.

Application filed April 23, 1923. Serial No. 634,168.

To all whom it may concern:

Be it known that I, FRED A. BROWN, a citizen of the United States, a resident of the city of Los Angeles, county of Los Angeles, and State of California, have invented new and useful Improvements in Wire-Grounding Devices, of which the following is a specification.

This invention has to do with a wire grounding device, and it is an object of the invention to provide a device for ground wires being strung onto or removed from poles, or the like, to protect workmen handling the wires.

15 Wires being strung onto or removed from poles, or the like, are usually dead while they are being handled; however, it occasionally happens that a wire while being strung comes in contact with an energized wire, causing 20 injury to the workmen handling the wire. Accidents of this kind are usually caused by the wire being handled sagging into contact with a live wire, or by its whipping or snapping up into engagement with a live 25 wire when it is being pulled tight.

It is an object of this invention to provide a device for grounding a wire while it is being strung or taken down so that the workmen are protected against the danger above 30 outlined, in the event that the wire becomes energized.

Another object of this invention is to provide a device of the character just specified which is simple and convenient to use and 35 therefore commercially practical.

The various objects and features of the invention will be best and more fully understood from the following detailed description of a typical preferred form of the 40 invention, throughout which reference is had to the accompanying drawings, in which:

Fig. 1 is a view showing a typical pole adapted to carry electric wires, equipped 45 with the device provided by this invention so that wires being strung on or removed from it are grounded;

Fig. 2 is an enlarged sectional view taken as indicated by the line 2—2 on Fig. 1;

50 Fig. 3 is a view taken as indicated by the line 3—3 on Fig. 2; and

Fig. 4 is a detail sectional view, taken as indicated by the line 4—4 on Fig. 3.

In the drawings, numeral 10 designates a 55 pole, provided at its upper end with the usual form of cross-arm 11. The cross-arm 11

is provided with a plurality of insulators 12, adapted to carry the wires to be supported by the pole.

The device provided by this invention includes, generally, a contact 13 and a grounding conductor 14. The contact 12 is, in accordance with my invention, adapted to be arranged or mounted on the cross-arm 11 in a manner so that it will be in position to 60 make contact with a wire 15, arranged over, or otherwise arranged in connection with, the cross-arm. In the particular situation illustrated in the drawings, the cross-arm 11 is formed of wood and is substantially 65 square in cross sectional configuration, so, therefore, the contact is provided with a body part adapted to be mounted on this particular type of cross-arm. It is to be understood that the term cross-arm as used 70 throughout this specification and in the appended claims is intended to include in like or similar devices or constructions to which this invention may be applicable. The body may include two jaws 16 and 17 adapted to 75 be arranged at opposite sides of the cross arm 11 and a connecting part 18 which joins the upper ends of the jaws and is adapted to engage the top of the cross arm. The body may be advantageously formed of a 80 single metal plate, and is preferably 85 designed and proportioned so that it can be conveniently arranged on the cross-arm, in the manner illustrated in the drawings. It is to be distinctly understood, of course, that 90 the broader aspects of my invention are not in any way limited to this or any other specific form of body for the contact 13, as it is obvious that the contact may be varied in its construction and arrangement to suit the 95 particular device or devices in connection with which it is adapted to be used.

In accordance with my invention I provide means for securing the contact in position in connection with the cross-arm. I 100 find it convenient to make the securing means in the form of a clamping device and when the contact has a body such as I have hereinabove described I find it convenient to provide a clamping screw 19 in connection 105 with one of the jaws of the body so that it can be actuated to engage or clamp against the cross-arm in a manner to securely retain the body in position thereon. In practice the clamping screw 19 is preferably provided with a head 20, which can be conveniently manipulated by hand. It will, of 110

course, be obvious that other forms of securing means may be employed, and that the particular form of securing means used in any given case will depend more or less 5 upon the details of construction of the contact and upon the type or form of device on which the contact is adapted to be mounted.

In accordance with the preferred form of my invention, I provide means for guiding 10 the wire 15 in contact with a part of the body. The form of guiding means which I have illustrated in the drawings includes two spaced projections extending from a part of the body, which projections are preferably in the form of rollers 21 carried on pivot pins 22. The pivot pins 22 preferably extend from the body in a manner so that they carry the rollers at the connecting part 15 of the body, causing the guide means to 20 guide the wire 15 in contact with the connecting part. In practice I prefer to crown the outer surface 23 of the connecting part somewhat so that it will make good contact with a wire 15 being drawn over it. When 25 the guide means is of the type hereinabove described, that is, when it includes a pair of spaced projections, such as rollers, or the like, it is desirable to provide means for retaining the wire 15 in position between the 30 rollers. In the form of my invention illustrated in the drawings I provide a gate 30 which, when closed, extends between the outer end portions of the rollers in the manner clearly illustrated in Fig. 3. One end of 35 the gate 30 is pivotally connected with one of the pivot pins 22 by means of a suitable pivot pin 32, while the other end is adapted to be releasably connected with the other pivot pin 22 by means of a suitable spring 40 catch 33. The particular spring catch which I have illustrated includes a single spring member attached to the pivot pin and provided with a hook part 34 which operates to hold the gate. The spring catch is designed 45 so that it automatically catches the gate upon its being closed and releases the gate when depressed. The gate 30 is particularly desirable when the device is used in situations where the wire 15 is apt to whip in a 50 manner to lift out of position from between the rollers 21. It will be obvious, of course, that the gate is provided mainly as an extra safety device and that it may in practice be eliminated.

55 The grounding conductor includes an insulated wire 40, having one end connected with the contact 13 and the other end adapted to be connected with the ground. In the drawings I have illustrated the wire 40 connected with 60 the jaw 16 of the body of the contact by means of a suitable screw 41. In practice it is desirable to connect the other, or ground, end of the wire 40 with a pipe line or other part that is well grounded, or to provide it 65 with a metal stake 45, for instance, in the

form of a piece of pipe that may be driven or otherwise arranged in the ground so that it has good contact therewith.

In operation the contact 13 is arranged in connection with the cross-arm 11 by placing the body over the cross arm and tightening the securing screw 19. The wire 15, to be strung on the cross-arm or to be taken down, is arranged in connection with the contact 13 by arranging it between the rollers 21 so 70 that it contacts with the connecting part 23. When the wire is thus arranged between the rollers it is made secure by closing the gate 30. The grounding conductor is made ready for operation by connecting it with ground, 75 for instance, by driving the stake 45 into the ground or by connecting the wire 40 with a grounded member. The wire 19 can be moved in either direction across the cross-arm 11 and, in the event that it contacts 80 with a live wire, the current will pass through the contact 13 and be carried to the ground by the grounding conductor.

It will be obvious that the device provided by the present invention thus operates 90 to protect workmen handling the wire 15 so that they are not injured in the event that the wire becomes energized. When it is desired to remove the device provided by the present invention it is merely necessary to release the securing screw 19 and remove the contact from the cross-arm and release the grounding conductor from its connection with the ground.

Having described only a typical preferred 100 form of my invention I do not wish to limit myself to the specific details hereinabove set forth but wish to reserve to myself any changes or variations that may appear to those skilled in the art or fall within the 105 scope of the following claims.

Having described my invention, I claim:

1. A device for grounding a wire being worked on a cross arm including, a contact adapted to be arranged at the cross arm to be engaged by the wire and clamp means for mounting the contact on the cross arm. 110

2. A device for grounding a wire being worked on a cross arm including, a contact adapted to be arranged at the cross arm and embodying a part adapted to be engaged by the wire and means for guiding the wire so that it engages said part, and a grounding conductor connected with the contact. 115

3. A device for grounding a wire being worked on a cross arm including, a part adapted to be arranged at the cross arm to be engaged by the wire, means for mounting said part at the cross arm, means for guiding the wire so that it engages said part, and a grounding conductor connected with the contact. 120

4. A device for grounding a wire being worked on a cross arm including, a part adapted to be arranged at the cross arm and 125

embodying a part adapted to be engaged by the wire and means for guiding the wire so that it engages said part, embodying spaced projections at said part adapted to have the wire arranged between them.

5 5. A device for grounding a wire being worked on a cross arm including, a contact adapted to be arranged at the cross arm and embodying a part adapted to be engaged by the wire and means for guiding the wire so that it engages said part embodying two spaced rollers projecting from said part and adapted to have the wire arranged between them.

10 15. 6. A device for grounding a wire being worked on a cross arm including, a contact adapted to be arranged at the cross arm and embodying a part adapted to be engaged by the wire and means for guiding the wire so that it engages said part embodying a pair of spaced projections extending from said part and a member extending between the projections at a point spaced from said part.

15 20. 7. A device for grounding a wire being worked on a cross arm including, a contact adapted to be arranged at the cross arm and embodying a part adapted to be engaged by the wire and means for guiding the wire so that it engages said part embodying a pair of spaced projections extending from said part and a releasable member extending between the projections at a point spaced from said part.

25 30. 8. A device for grounding a wire being worked on a cross arm including, a contact adapted to be arranged at the cross arm and embodying a part adapted to be engaged by the wire and means for guiding the wire so that it engages said part embodying a pair of spaced projections extending from said part and a gate adapted to close across the outer parts of the projections.

35 40. 9. A device for grounding a wire being worked on a cross arm including, a contact adapted to be arranged at the cross arm and embodying a part adapted to be engaged by the wire and means for guiding the wire so that it engages said part embodying a pair of spaced projections extending from said part, a gate pivotally connected with one projection, and means for releasably connecting it with the other projection.

45 50. 10. A device for grounding a wire being worked on a cross arm including, a contact adapted to be arranged at the cross arm and embodying a part adapted to be en-

gaged by the wire and means for guiding the wire so that it engages said part embodying a pair of spaced projections extending from said part, a gate pivotally connected with one projection, and spring catch means for releasably connecting it with the other projection.

55 60. 11. A device for grounding a wire being worked on a cross arm including, a contact embodying a body having jaw parts adapted to receive the cross arm and a part adapted to engage the wire.

65 70. 12. A device for grounding a wire being worked on a cross arm including, a contact embodying jaws adapted to receive the cross arm, a part adapted to be engaged by the wire, and means for guiding the wire in engagement with said part.

75 80. 13. A device for grounding a wire being worked on a cross arm including, a body having two spaced jaws adapted to receive the cross arm, and a connecting part extending between the upper ends of the jaws and adapted to be engaged by the wire, a screw carried by one of the jaws for clamping the body on the cross arm, a pair of spaced pivot pins extending upwardly from the connecting part, rollers carried on the pins to guide the wire in engagement with the connecting part, a gate pivotally connected with the upper end of one of the pins, spring catch means for releasably connecting the gate with the other pin, a wire having one end connected with the body, and a grounding stake connected with the other end of the wire.

85 90. 14. A device for grounding a wire being worked on a cross arm including, a contact adapted to be arranged at the cross arm, and embodying a part adapted to be engaged by the wire and means for guiding the wire in contact with said part.

95 100. 15. A device for grounding a wire being worked on a cross arm including, a part adapted to be arranged at the cross arm to be engaged by the wire, means for detachably mounting said part at the cross arm, and means for grounding the wire in engagement with said part.

105 In witness that I claim the foregoing I have hereunto subscribed my name this 31st day of March, 1923.

FRED A. BROWN.
